United States Patent

[19]

Brian

[11] Patent Number: Des. 414,480

[45] Date of Patent: ** Sep. 28, 1999

[54] STROBE LAMP ILLUMINATOR

5,773,808 6/1998 Laser .

[75] Inventor: Steven R. Brian, Bedford, N.H.

Primary Examiner—Susan J. Lucas
Attorney, Agent, or Firm—Orrick, Herrington & Sutcliffe
LLP

[73] Assignee: CiMatrix, Canton, Mass.

[57] CLAIM

[**] Term: 14 Years

The ornamental design for strobe lamp illuminator, as shown
and described.

[21] Appl. No.: 29/085,359

DESCRIPTION

[22] Filed: Mar. 20, 1998

Related U.S. Application Data

[62] Division of application No. 08/906,679, Aug. 5, 1997.

FIG. 1 is a perspective drawing of the strobe illuminator, and
also shows in broken lines a base on which the strobe
illuminator may be mounted (the base does not form a part
of the claimed design and is not shown in the other figures);
FIG. 2 is a front view in which a circular mounting ring is
mounted between two concentric circular optical filters;
FIG. 3 is a back view having a central aperture and a
arcuate-shaped camera stand on which a camera or CCD
device may be rested;

[51] LOC (6) Cl. 14-02
[52] U.S. Cl. D14/116; D26/24
[58] Field of Search 235/435, 468,
235/462, 472, 455, 491; 315/227 R; D26/24;
250/271, 566, 569; D14/116

FIG. 4 is a top view of the strobe illuminator showing the
mounting ring projecting from the front of the strobe illu-
minator and the arcuate-shaped camera rest projecting from
the back of the strobe illuminator;

[56] References Cited

FIG. 5 is a bottom view of the strobe illuminator; and,
FIGS. 6 and 7 are right and left side views, respectively,
thereof.

The strobe lamp illuminator is designed to illuminate and
thereby enable the reading of optically readable codes
printed in ultraviolet materials.
